CASTOR

Frederic A. Brayley, Dorchester, Mass.

Application December 24, 1934, Serial No. 759,055

1 Claim. (Cl. 16—24)

My present invention relates to castors and more particularly to ball bearing castors.

The principal object of my invention is an improved castor;

Another object is an improved ball bearing castor;

Another object is an improved castor having a bearing surface comprising a single ball;

Still another object is an improved bearing case for a ball bearing castor;

Other objects and novel features comprising the construction and operation of my improved castor will appear as the description of the same progresses.

Referring to the drawing illustrating my invention;

Fig. 1 is partial elevation and cross-section, the castor unit being in elevation;

Fig. 2 is a typical cross-section taken through the castor unit and the leg of a chair or other piece of furniture;

Fig. 3 is a plan view of the castor shown in Figs. 1 and 2;

Fig. 4 is a cross-section similar to Figs. 1 and 2 showing a modification of the castor casing, and

Fig. 5 is another modification showing a still further modification of the castor casing.

Referring more in detail to the drawing, 10 indicates the leg of a chair, for instance, the end 30 of which has been recessed at 11 to receive the castor casing 12 which in Figs. 1 and 2 consists of a cylindrical shell open on the bottom and closed at the back. Over the open end is placed a disc 13 which is provided with spur members 14 disposed at ninety degrees to the disc 13 and adapted to be driven into the chair leg 10.

The disc 13 is the same in all the various views and is attached to the casing 12, 12a or 12b by means of screws 15. The inner central portion 40 of the disc 13 is recessed and counterbored at 16 to receive a ball 17 a portion of the periphery of which protrudes through the disc as illustrated in the drawing.

In Figs. 1 and 2 I have provided a screw pin 45 18 at the back of the casing 12 against which the

ball 17 rests and revolves the opening 16 in the disc 13 acting as a second point of contact.

In Fig. 4 I have provided a back support 19 struck up from the metal comprising the casing 12a. This support and bearing member 19 also acts as a stiffener for the back of the casing 12a. If necessary or desirable I may make the whole back of the casing 12a inwardly converging in a funnel-like manner without piercing through the casing, instead of the central portion as 10 shown in the drawing.

In Fig. 5 I show a modification of the casing as indicated at 12b in which I have provided a cup shaped bearing surface 20.

In all the figures illustrating my invention it 15 will be noted that I have provided a two point contact, the opening 16 being the same in all cases being a ring surface around the ball 17. In Fig. 5 the second point is the cup surface 20 which is identically the same as the ball periphery 20 and extends half around the ball 17. In all other cases the second point contact is directly at the back of the ball 17 either by means of the pin 18 or the cone point 19.

Having thus described my invention what I 25 claim as new is:

An improved castor comprising in combination, a cylindrical casing open at one end and closed at the other end, the said closed end comprising a depressed central portion the side walls of 30 which are conically shaped, said conically shaped walls being depressed from the horizontal closed end of the casing, a concaved bearing surface located on the inside apex portion of said depressed central portion, a cover disc located on 35 the open end of said cylindrical casing and having a central opening concaved on the inner side, means for attaching said disc to said casing, spurs located on the outer periphery of said disc and parallelly disposed to the side walls of said 40 casing, a ball seated against the concaved bearing surface of said depressed portion and engaging with the inner concaved surface of the central opening of said disc.

FREDERIC A. BRAYLEY. 45
